Primary Examiner — Mary Ann Calabrese(74) *Attorney, Agent, or Firm* — Banner & Witcoff, Ltd.(57) **CLAIM**

The ornamental design for a pliers rack, as shown and described.

DESCRIPTION

FIG. 1 is a top, front, left perspective view of a pliers rack showing my new design;

FIG. 2 is a top view thereof;

FIG. 3 is a front view thereof;

FIG. 4 is a left side view thereof, wherein the right side is a mirror image of FIG. 4;

FIG. 5 is a rear view thereof; and,

FIG. 6 is a bottom view thereof. The broken lines are features that form no part of the claim design.
